[57] CLAIM

The ornamental design for a drawer pull, as shown and described.

DESCRIPTION

FIG. 1 is a front view of a drawer pull embodying the design of this invention;

FIG. 2 is a top view of the drawer pull shown in FIG. 1; FIG. 3 is a side elevational view taken from the right side of FIG. 1, the left side being substantially a mirror image thereof;

FIG. 4 is a cross-sectional view taken generally along line 4—4 of FIG. 1;

FIG. 5 is a fragmentary enlargement of the upper portion of FIG. 4; and,

FIG. 6 illustrates the application of the drawer pull of the invention to a file drawer.

The drawer pull of this invention, when mounted on a drawer, is visible primarily only from the front side thereof, as shown in FIGS. 1 and 6. The other sides, including the back, are nonornamental and substantially hidden when mounted on a drawer and are therefore shown in broken lines in FIGS. 2 and 3.

The broken lines as appearing in FIG. 6 are solely for the purpose of illustrating environmental structure, and form no part of the inventive design.
